UNITED STATES PATENT OFFICE

2,468,133

TOURNIQUET

Gregory B. Sullivan, Chicago, Ill.

Application August 13, 1945, Serial No. 610,505

3 Claims. (Cl. 128—327)

1

My invention relates to tourniquets, and more particularly to the means for holding the same in engagement with the limb treated.

One object of the invention is to provide a tourniquet which is normally in the form to be used and quickly mountable on and adjustable around the limb to stop bleeding at the earliest possible moment.

A further object is to construct the tourniquet with means to evenly distribute its pressure, so that its construction may be uniform and its wear comfortable.

Another object is to include a factor operative to constrict the tourniquet to its smallest diameter, so that its tendency will always be to close around and cling to the limb, whatever the girth of the latter may be.

An important object is to design the tourniquet along lines of simplicity and with a minimum number of parts consistent with efficient construction and operation.

With the above objects in view and any others which may suggest themselves from the description to follow, a better understanding of the invention may be had by reference to the accompanying drawings, in which—

Fig. 1 is an elevation of the improved tourniquet;

Fig. 2 is a right-hand side view;

Fig. 3 is a fragmental view of the main portion in the region of one end;

Figs. 4 and 5 are, respectively, sections on the lines 4—4 and 5—5 of Fig. 3;

Fig. 6 is an enlarged vertical section of a binding device shown in the upper part of Fig. 1;

Fig. 7 is a cross-section on the line 7—7 of Fig. 6; and

Fig. 8 is a longitudinal section of the outer wall structure of the tourniquet, taken on the line 8—8 of Fig. 3.

In accordance with the foregoing, the basic element of the tourniquet is a long rubber tube 10 having closed ends 11 and a structure similar to a bicycle tire inner tube. The tube 10 is designed to be formed into a coil and to be inflated by way of a standard air valve 12.

In order that the tube 10 may apply as a tourniquet, it is enclosed in a casing 13 of similar form, the ends of the casing being flattened as indicated at 14. The casing 13 is of leather and with a lap joint 15 on its outer side. The casing has an opening at a medial point for the passage of the inflation valve 12 from the inner tube 10; and a portion of the overlap 15 is left open in the same zone to facilitate the insertion and removal

2

of the inner tube. The open portion of the casing is secured by lacing 16 to properly retain the inner tube.

As indicated in Fig. 1, the casing 13 overlaps 5 at its ends to form a band whose diameter may differ in accordance with the extent of the overlap. When such diameter has once been determined, means for securing the casing are provided in the form of an external strap 17 of heavy duck 10 or like fabric, such strap encircling the casing and also being perforated for the passage of the inflation valve 12.

Figs. 1 and 6 show a feed and securing means for the strap 17. Thus, a light metallic con-

15 tainer 18 is provided alongside the casing, the same having a spindle 19 on which is wound a roll 20 of the strap material 17. This material is paid out from the roll 20 to wrap around the casing and enter a bottom chamber 21 of the

20 container 18 with its leading end 22. Here a clamping bar 23 pivoted at 24 in the chamber 21

10 may be applied by means of an externally directed handle 25 to wedge the leading end 22 of the strap against the floor 26 of the container 18, thus

25 securing such leading end firmly to the container. The spindle 19 extends out on one side of the

20 container 18 to receive the inner end of a spiral spring 27, the outer end of the same being se-

25 cured to a pin 28 projecting from the side wall

30 of the container. The tendency of the spring 27 is to wind the strap material 17 onto the roll

20 20, so that the strap becomes closely wound around the casing 13 automatically, irrespective

35 of the diameter assumed by the casing. When such diameter is determined and the strap applied

30 as stated, a fluted cross bar 29 is applicable to

the strap on the inside of the container to wedge

35 the strap tightly against the roof 30 of the same. The cross bar 29 has headed end pieces 31 which

40 pass through arcuate slots 32 in the side walls of

the container 18, such slots departing from the

45 applied position of the cross bar in a downward

direction. Thus, when it is desired to release

45 the strap 17, the end pieces 31 of the cross bar

50 are pulled back through the slots 32 from the

45 applied position of the cross bar to rest in the

55 lower portions of the slots until again required

for clamping purposes. It will be understood

50 that the spring 27 will be sufficiently strong to

cause the strap 17 to exert a firm hold on the

55 casing 13.

With the tourniquet constituted as described, it is always in the toroidal or band form suitable for application to a limb, so that it may be slid on the same without delay or preliminary adjust-

ment. In other words, the casing 13 will expand in response to the progressive girth of the limb, and the strap 17 will pay out at the same time until the position at which the tourniquet is applicable is reached. The strap may now be secured as described to hold the tourniquet in place, and the inner tube 10 inflated by means of a hand pump or other compressed air source until the required constriction of the limb has been accomplished.

I have provided an additional expedient which will tend to close the tourniquet around the limb at all times and irrespective of the girth of the same, the drawing shows that the external walls of the casing 13 carry a pair of longitudinal cloth hems or bindings 33 which are stitched or otherwise secured to the casing at 34 and close endwise with cross pieces 35. The longitudinal hems 33 form sheaths for a pair of longitudinal bands 36 of spring steel which have a winding tendency. The bands 36 are thus disposed in a manner to impose a constricting influence on the casing 13 at all times, this influence not only aiding the application of the tourniquet, but also maintaining the engagement of the same in case the strap 17 becomes loosened, partly detached through some circumstance or otherwise disengaged from the casing 13.

It will be evident from the above description that the novel tourniquet is an appliance having a high degree of efficiency, since it is ready for immediate application to a limb at any desired point without preliminary or special preparation or any involved attention or work after it has been applied to secure it. This factor is of importance when much may depend on how soon or how quickly a tourniquet is applied. Further, the latter is a light and firm assembly which is easy to handle and has no delicate or extra parts to be attended to during its application to consume extra work and time. Further, the encircling form of the tourniquet makes its engagement uniform and comfortable. Finally, the tourniquet is composed of a small number of parts which are simple and easy to handle.

While I have described the invention along spe-

cific lines, various minor changes or refinements may be made therein without departing from its principle, and I desire to consider such changes and refinements as coming within the scope and spirit of the appended claims.

I claim:

1. A tourniquet comprising an elongated member coiled to overlap its ends, and self-winding spring means carried by the member and tending to exert a progressive constricting influence on the member when the same is applied.
2. A tourniquet comprising an elongated member coiled to overlap its ends, and a longitudinal self-winding spring band wrapped around the member and tending to exert a progressively constricting influence on the member when the same is applied.
3. A tourniquet comprising an elongated inflatable member coiled to overlap its ends, an inflating valve projecting from the outer wall of the member and midway between its sides, a wrapper encasing the member and having a longitudinal opening in its outer wall for the passage of said valve and the insertion or removal of said member, means to gather the sides of the opening when the member is contained in the casing, and a pair of yieldable longitudinal bands wrapped around the outer casing wall inwardly of the sides thereof, such bands tending to wind the encased member with a constricting effect when applied.
